Filed July 1, 1968, Ser. No. 12,558

Term of patent 14 years

Int. Cl. D16—08

U.S. Cl. D57—1

FIG. 1

FIG. 2

FIG. 1 is a front view of a pair of sun spectacles showing my new design;

FIG. 2 is a side view of said pair of sun spectacles taken from the right side thereof as viewed in FIG. 1, the side not shown being of substantially the same appearance as the side shown; and

FIG. 3 is a top view thereof.

The temples are shown broken away in FIG. 3 for convenience of illustration.

The dominant features of my design reside in those portions shown in full lines.

I claim:

The ornamental design for a pair of sun spectacles, substantially as shown and described.
